US00D698021S

(12) **United States Design Patent**
Nering et al.

(10) **Patent No.:** US D698,021 S
(45) **Date of Patent:** ** Jan. 21, 2014

(54) **SURGICAL FASTENER**

(71) Applicants: **Robert Nering**, Stockton, NJ (US);
Simon Cohn, Lebanon, NJ (US);
Anthony Miksza, Nazareth, PA (US);
Matthew David Daniel, Ann Arbor, MI (US); **Jeremy David Jarrett**, Cincinnati, OH (US)

(72) Inventors: **Robert Nering**, Stockton, NJ (US);
Simon Cohn, Lebanon, NJ (US);
Anthony Miksza, Nazareth, PA (US);
Matthew David Daniel, Ann Arbor, MI (US); **Jeremy David Jarrett**, Cincinnati, OH (US)

(73) Assignee: **Ethicon, Inc.**, Somerville, NJ (US)

(**) Term: **14 Years**

(21) Appl. No.: **29/447,564**

(22) Filed: **Mar. 5, 2013**

Related U.S. Application Data

CLAIM

The ornamental design for a surgical fastener, as shown and described.

DESCRIPTION

FIG. 1 is a perspective view of a surgical fastener, showing our new design;

FIG. 2 is a front elevation view of the surgical fastener shown in FIG. 1;

FIG. 3 is a left side view of the surgical fastener shown in FIG. 1;

FIG. 4 is a right side view of the surgical fastener shown in FIG. 1; and,

FIG. 5 is a top plan view of the surgical fastener shown in FIG. 1.

The broken lines in the drawings form no part of the claimed design for a surgical fastener.
